UNITED STATES PATENT OFFICE.

HARRY C. RICKENBACH, OF PITTSBURGH, PENNSYLVANIA, ASSIGNOR TO JAS. H. MATTHEWS & CO., OF PITTSBURGH, PENNSYLVANIA, A CORPORATION OF PENNSYLVANIA.

MACHINERY FOR MAKING DIES.

Application filed November 29, 1921. Serial No. 518,565.

To all whom it may concern:

Be it known that I, HARRY C. RICKENBACH, residing at Pittsburgh, in the county of Allegheny and State of Pennsylvania, a citizen of the United States, have invented or discovered certain new and useful Improvements in Machinery for Making Dies, of which improvements the following is a specification.

10 My invention relates to machinery for making dies. The dies here in contemplation are such as are employed for impressing some legible or identifying mark upon the surface of an article of metal; these dies 15 are made of short lengths of tool-steel rod, bearing upon one end, in sharp-edged relief and in reverse, the character or design to be impressed. In service, the die, held in the hand with its cutting face against the 20 surface to be marked, is struck with a hammer upon the opposite end (or a power press may be used), and thus the desired impression is made upon the surface under treatment. It is to the forming of the cutting 25 face of such a die that my invention is directed.

Various processes have hitherto been resorted to, in order to effect this shaping of the cutting face or working face of the die, 30 including casting, cutting, and swedging. The operation which my machine performs is essentially a swedging operation,—that is to say, an operation in which a blank in solid state, subjected to pressure, is shaped 35 under a matrix; the material of the blank is squeezed into the interstices of the matrix, and so the desired shaping of the face of the blank is achieved. The blank of tool steel is while this operation is in progress 40 in still unhardened condition; the matrix is of hardened tool steel. When shaping has been effected the blank is hardened. Trimming and sharpening of the otherwise completed die may be resorted to, either before 45 or after hardening.

More particularly, the swedging operation which my machine performs is one in which matrix and the blank when brought face to face stand, not in exact axial alignment, but with their axes inclined at a small angle, the one to the other, and in which while the swedging pressure is exerted the remote end of one of the two bodies mentioned moves orbitally about the axis of the

other; and thus the swedging pressure, concentrated in a line extending radially from the centers of matrix and blank, sweeps with each orbital swing the entire surfaces of both these bodies. And this orbital swing, while pressure continues, being repeated again and again, the metal of the blank is gradually raised into close conformity to the shaping face of the matrix.

Referring to the drawings, Figure I is a view in plan from above of a machine embodying my invention. Figure II is a view in vertical section on the plane indicated by the line II—II, Figure I. Figure III is a view to larger scale showing in front elevation the matrix and its carrier as it appears mounted in the machine ready for operation. It is such a view as would be got if, referring to Figure II, the machine parts to the right of the line III—III were cut away, and the remainder of the machine 65 were viewed from right to left. Figure IV is a view in horizontal section on the plane indicated at IV—IV, Figure III. Figure V is a fragmentary view to scale corresponding to Figures III and IV, showing 70 in elevation the remote end of the matrix carrier and the connection by which it is driven. Figure VI is a view in transverse section on the plane indicated at VI—VI, 75 Figure V.

Referring first to Figure II, the machine there illustrated includes means for carrying a matrix M (cf. Figs. III and IV) and also a carrier for a blank B to be operated upon. These two bodies are shown in Figure II to be borne by the machine in face to face contact, but not in exact axial alignment.

The remote end of the matrix carrier in which the matrix itself is centered is shown 95 to be remote from the prolonged axis of the blank by the interval $a b$ (cf. Fig. V).

In the operation of the machine these two bodies are subjected to a relative movement, the axis of the one moving orbitally 100 around the axis of the other, and while my invention is not specifically limited to this particular arrangement, I find it convenient and preferable to mount the blank in the machine so that during operation it has no 105 other movement than a minute forward feed which progresses as its face is gradually swedged, while the matrix carrier and the

matrix are subjected to the orbital motion which has been mentioned around the prolonged axis of the blank.

The blank B, as shown in Figures I and II, is mounted in a block 1, and removably secured therein by means of a hand-operated set screw 2; the block 1 is pivoted in a slide 3 and secured by a hand-operated lock 4. This particular construction makes possible the ready removal of a finished article and the introduction of a new blank while the general assembly of the machine is not at all disturbed. The slide 3 moves horizontally in the bed of the machine and is moved in a right and left movement, as shown in these figures, by a screw 5 driven by a hand wheel 6. It is this screw drive through which swedging pressure is exerted.

20 The matrix carrier 7 is elongate. It is provided at one end with a seat for the matrix M, which seat conveniently consists of blocks 8 and 9, carried in a frame 10, and constituting clamping members secured 25 by a set screw 11. The further characteristic features of this matrix carrier are, first, that it is so constructed that when mounted in its frame, presently to be described, it is secure against rotation on its own axis, and in this connection it is to be noted that that end of the matrix carrier in which the matrix is carried is essentially 30 of the square shape indicated at 12, and that the rim or edge of this square end is rounded. Second, this matrix carrier is provided at a region remote from the matrix seat, but intermediate the length of the carrier, with a spherical bearing surface 13, whose center of curvature lies (with such 35 tolerance as the operation admits of) at the center of the working face of the matrix M when in place in its seat.

This matrix carrier so characterized is borne in a frame 14 in such manner as to be 40 subject to the movement already defined, that is to say, a movement in which, while matrix and blank remain in face to face contact, the remote end of the matrix carrier moves orbitally around the prolonged axis of the blank. The blank itself being 45 secured against rotation on its axis, the matrix carrier also is secured against rotation upon its axis. To accomplish the end indicated, the frame 14 is provided with an 50 open end 15 of square shape within which the square end of the matrix carrier lies, as is clearly shown in Figures III and IV. The frame is further provided with a spherical seat 16 for the spherical bearing surface 13 of the carrier, the assembly being 55 in this respect clearly indicated in Figure IV.

60 Into proximity with the remote end of the matrix carrier extends a power driven shaft 17 (shown at the extreme left in Fig-

ures I and II) which power shaft is axially aligned with the blank B when in place in its carrier ready for the swedging operation. A crank connection is made between this power driven shaft 17 and the remote 70 end of the matrix carrier 7, to the end that as the shaft rotates the remote end of the carrier 7 will describe the orbital motion already defined. The construction is that illustrated in Figures V and VI, where two blocks 18 and 19 are shown, the block 18 being rigidly borne on the shaft 17, and the block 19 affording a bearing for the end 7 of the matrix carrier and within which the matrix carrier is freely revoluble or, to speak with greater accuracy, the block is freely revoluble about the axis of the matrix carrier. These two blocks are adjustable 75 transversely of the axis of the shaft 17 as is indicated by the bolt and slot connection 80 shown in Figures V and VI. Thus the remote end of the matrix carrier is driven orbitally around the prolonged axis of the blank, and furthermore provision is made 85 that the eccentricity of the remote end of the matrix carrier with respect to the axis of the blank may be fixed at any degree desired within practical range. For I find that, according as the design which is to be 90 developed in the blank is of larger or smaller surface extent, it is desirable to increase or diminish the degree of this eccentricity.

The frame 14 is shown to be made up of 95 castings properly bolted together for facility in assembling and economic replacement of worn parts. These features however form no part in my present invention.

The operation involves a preliminary 100 equipping of block 1 with blank B, and of matrix carrier 7 with a matrix M. The pivotal mounting of block 1, the securing set screw for blank B, the proper recessing of 105 the end of the matrix carrier, and the provision of the set screw 11, permit the ready preparation of the machine in this respect without any taking down of the machine structure, and permit also the repeated replacement of a finished blank with an unformed blank as operation progresses. When the machine is so provided with matrix and blank, the parts being in the general position indicated in Figures I and II, power shaft 17 is driven and the described orbital motion is imposed upon the matrix M. While the matrix M is so moving, the hand wheel 6 is turned, and the blank B is advanced into contact with the matrix and pressure is exerted upon that contact, and is 110 continuously exerted as the substance of the blank itself under this pressure is minutely replaced, and the face of the blank brought into correspondence with the face of the matrix. When by continued application of 115 pressure and continued orbital motion of the matrix the blank is developed to the full ex-

tent that the machine is intended to achieve, pressure is relieved, the screw 5 is driven in the opposite direction, the block 1 unlocked and swung aside (upward), the set screw 2 is eased, and the completed blank B is removed. Another is put in its place and locked by the screw 2. The block is then swung back into position and locked by the lock 4, and then the operation is repeated. The even distribution of the swedging pressure results in a die of uniform quality throughout its working face.

I have in the foregoing description made the blank B the body subject to the straight away thrust of the screw 5. It will be understood that the essential requirement is that the two bodies M and B, while the relative orbital motion described is maintained, shall be compressed one upon the other, and while I do not limit my invention to this specific arrangement, I find it advantageous and simple to make the blank B the movable body in this right-line direction to afford the swedging pressure.

Details of structure are elaborated here in an exemplary way. The invention is of course not limited to such matters.

I claim as my invention:

1. A machine for swedging the faces of dies, including the combination of a carrier provided with a seat for one of the two co-acting bodies (blank and matrix) and with a spherical bearing surface remote from said seat, the center of curvature of said bearing surface being coincident with the center of the face of the body referred to when in place in said seat, and a frame for said carrier including a spherical socket for said bearing surface and a keeper adapted to engage said carrier adjacent the aforementioned seat therein and by such engagement, while leaving the carrier otherwise free, preventing axial rotation thereof, substantially as described.

2. A machine for swedging the faces of dies, including the combination of a carrier polygonal at one end in cross section and at such polygonal end provided with a seat for one of the two co-acting bodies (blank and matrix) and provided further with a spherical bearing surface remote from said seat, the center of curvature of said bearing surface being coincident with the center of the face of the body referred to when in place in said seat, and a frame for said carrier including a spherical socket for said bearing surface and a polygonal keeper adapted to engage the polygonal end of said carrier, substantially as described.

3. A machine for swedging the faces of dies, including the combination of a carrier provided with a seat for one of the two co-acting bodies (blank and matrix) and with a spherical bearing surface remote from said seat, the center of curvature of

said bearing surface being coincident with the center of the face of the body referred to when in place in said seat, a frame for said carrier including a spherical socket for said bearing surface and a keeper adapted 70 to engage said carrier adjacent the aforementioned seat therein and by such engagement, while leaving the carrier otherwise free, preventing axial rotation thereof, and means for imparting to the end of said carrier remote from the seat above mentioned orbital motion about an axis passing through the center of such body and extending angularly with respect to the axis of the carrier, substantially as described. 75 80

4. A machine for swedging the faces of dies, including the combination of a carrier provided with a seat for one of the two co-acting bodies (blank and matrix) and with a spherical bearing surface remote 85 from said seat, the center of curvature of said bearing surface being coincident with the center of the face of the body referred to when in place in said seat, a frame for said carrier including a spherical socket 90 for said bearing surface and a keeper adapted to engage said carrier adjacent the aforementioned seat therein and by such engagement, while leaving the carrier otherwise free, preventing axial rotation thereof, means for imparting to the end of said carrier remote from the seat above mentioned orbital motion about an axis passing through the center of such body and extending angularly with respect to the axis of the carrier, and means for varying the radius of such orbital motion, substantially as described. 95 100

5. A machine for swedging the faces of dies, including the combination of a carrier provided with a seat for one of the two co-acting bodies (blank and matrix) and with a spherical bearing surface remote 105 from said seat, the center of curvature of said bearing surface being coincident with the center of the face of the body referred to when in place in said seat, a frame for said carrier including a spherical socket for said bearing surface and a keeper 110 adapted to engage said carrier adjacent the aforementioned seat therein and by such engagement, while leaving the carrier otherwise free, preventing axial rotation thereof, means for sustaining the other of the two coacting bodies in operative position opposite the body borne by said carrier, and means for moving, one relatively to the other, the bodies so carried, in a direction angular to the axis of said carrier. 115 120 125

In testimony whereof I have hereunto set my hand.

HARRY C. RICKENBACH.
